UNITED STATES PATENT OFFICE.

EDWARD H. MOYLE, OF LOS ANGELES, CALIFORNIA.

MORTAR FOR STAMP-MILLS.

1,121,118.

Specification of Letters Patent. Patented Dec. 15, 1914.

Application filed February 24, 1905. Serial No. 247,087.

To all whom it may concern:

Be it known that I, EDWARD HENRY MOYLE, a citizen of the United States, residing at Los Angeles, in the county of Los Angeles and State of California, have invented new and useful Improvements in Mortars for Stamp-Mills, of which the following is a specification.

This invention relates to improvements in 10 mortars, and the main object of my invention is to provide a means for distributing the ore to be crushed, to each stamp separately of the others, and to distribute the ore by circular means, or all around the 15 stamp.

Another object is to have free observation and access to the stamps when standing at the plate side.

Another object is to provide a means 20 whereby the stem-guide can be placed at the lowest possible position on the stem of the stamp.

Another object is to decrease the height 25 as much as possible, as well as the weight of the mortar.

Another object is to prevent the cupping or uneven wearing of the die and the stamp.

Another object is to reduce the liability 30 of breakage of the stamp-stem at the place where it enters the stamp-head.

Another object is to increase the capacity or crushing effect of the stamp with the least amount of sliming and with the same amount of horse-power.

35 Another object is to provide a means whereby the screen on the feeder side can be as large, or larger, than on the plate side.

Another object is to provide a means 40 which will avoid the constant attention of the attendant for keeping the ore feed-chute clear.

The accompanying drawings illustrate the invention.

Figure 1 is a plan view of a mortar 45 constructed with five stamps. Fig. 2 is a longitudinal, vertical section on the line W—W of Fig. 1. Fig. 3 is a transverse, vertical section on the line x—x, of Fig. 1. Fig. 4 is a plan of the mortar, showing a different 50 form of launder. Fig. 5 is a transverse, vertical section on the line y—y, of Fig. 4. Fig. 6 is an end elevation of the motar shown in plan, Fig. 4. Fig. 7 is a longitudinal, vertical, sectional view of a different 55 form of motar. Fig. 8 is a transverse, vertical, sectional view of the same. Fig. 9 is

a longitudinal, vertical view of another form of mortar. Fig. 10 is a broken sectional view similar to Fig. 9 showing another form of mortar.

In the operation of stamp mills, the system most generally used is to have one stamp regulate the feed of itself and of the other stamps, by having the ore conveyed through a rectangular chute-box at the 60 feeder side of mortar, said chute conveying the ore principally to the middle stamp and dropping at the back of stamp to take its place on the die to be crushed and distributed when the stamp is dropped; while 65 in the system shown in the accompanying drawing, the ore is conveyed to each stamp by a circular chute around each stamp, and therefore dropped evenly around the die, which prevents the cupping or uneven wear- 70 ing of the die. It also prevents the breaking of stems above the stamp-head, as the stamp is always striking squarely on ore. It also provides a means whereby the ore 75 can be fed mechanically or regularly to each stamp independently of the others, thereby obtaining the greatest crushing capacity.

In the accompanying drawings it will be noticed that as the ore is fed around the stamp, said stamp in raising and lowering 80 will release the ore, if necessary, thereby keeping the circular chute clear and also helping to distribute the ore around the stamp, as the stamp in its raising movement is revolved by the contact of the lift- 85 ing-cam and tappet which is located upon the stem (not shown).

It is not so material as to how the ore is 90 conveyed to one common point upon the plate side, although I have shown two systems in the accompanying drawing, either of which I wish to combine with the circular feeding device, but it is not necessary to have the discharge-screens all around the stamps, as shown, as the mortar can 95 be built with one or more screens as required.

Referring more particularly to the drawings, 1 indicates the mortar, which may be of any suitable shape and size, the one 100 shown in the drawings being rectangular and adapted to receive or be operated by five stamps of any desired or usual construction.

The mortar is provided with the usual 110 flange or base 2 which is perforated as at 3, by means of which it is secured in position.

Extending around the mortar, or on all sides thereof, is a screen 4, which is of the usual construction, and is secured in position by wedges 5. If desired, a splash-board, not shown, may be seated in grooves 6 in front of the screens. Chock-blocks 7 are located upon the inside of the mortar and have their inner faces covered with amalgamating plates in the usual manner.

Between the different dies 8, I prefer to arrange dividing walls or partitions 9, which preferably extend a slight distance above the upper faces of the dies, as shown in Fig. 2, although they may terminate at 15 a lower point, as indicated by dotted lines in said figure.

Extending entirely around the exterior of the mortar below the screens is a launder 10 which is adapted to receive crushed material from any of the screens and conduct it to the front of the mortar, where it terminates in a lip 11. In the form of mortar shown in Figs. 1, 2 and 3, channels 12 are formed through the mortar below the 25 stamps so as to conduct the material directly from the rear to the front without its having to pass around the ends of the mortar, thereby avoiding the possibility of overflowing the launder at the ends of the 30 mortar. In the form of mortar shown in Figs. 4, 5 and 6, where the launder extends around the mortar, the rear floor and wall are inclined from the central portion to each end, thereby causing the material to 35 freely flow down hill and be discharged through the inclined channels at the ends of the mortar.

The feeding of the ore to the mortar is effected by arranging a receptacle 13 having an inclined bottom divided into a plurality of sections, the sections forming the receptacle 13, having a central opening for receiving the stamp and inclining downwardly toward the stamp at all sides, so as 45 to form an ore guide or feed-chute 13 for each stamp and each of said top plate sections having a central opening for receiving the stamp so as to form a ring around each stamp of an internal diameter enough 50 larger than the diameter of the stamp-head 14 to permit of the ore passing between the head and the ring and thereby being dropped all around the stamp, said top plate is preferably formed with side portions or 55 walls removably fastened to the walls of the mortar and with a depressed bottom extending preferably at an angle to the plane of the stamps and forming ore guide or chute rings, the top plate constituting a 60 trough or receptacle for receiving the ore, said receptacle surrounding all the stamps and communicating from end to end of the mortar around all the stamps so that ore feeding thereinto will be distributed by 65 gravity and by agitating effect of the

stamps from end to end thereof, and will pass into the several ore guides directly around their respective stamps, giving a separate feed for each stamp, supplied from a common source. This will cause the ore 70 to be fed on to the die uniformly from all points which will increase the crushing capacity of each stamp and also avoid liability of breaking the stem 15 by having the ore evenly distributed over the face of 75 the die and causing the force of the shoe to be evenly distributed.

The annular feeding chute may be arranged horizontally in the top of the mortar, as shown in Fig. 3, or it may be inclined, as shown in Fig. 5, and it may be arranged concentrically relatively to the stamp-head, but I prefer to arrange it eccentrically, as shown in the drawings. In either case it is preferably provided with 85 a ring or neck 16 which fits within the top of the mortar and may be secured thereto by means of bolts 17.

A flange 18 may be formed at the upper end of the neck so as to rest on top of the 90 mortar and thereby assist in holding it in position. I prefer constructing the feed-chute as an integral part with the openings formed therein at the appropriate points for the passage of stamps, although each ring 95 may be formed separate, as shown in Figs. 7 and 8, which are secured to the top of the mortar in the same manner as with the integral construction.

In the form of mortar shown in Figs. 7 100 and 8, the partitions 19 between the respective stamps and dies are each shown extending substantially up to the feed rings and having formed or located in its lower portion a goose neck or passage 22, through 105 which water is introduced to the mortar from a pipe or manifold 23, at one side of the mortar, the water escaping from said goose neck or passage through recesses 20, forming with said passage 22, substantially 110 a T. The upper portion or bend of the goose-neck is located at such a distance above the normal surface of the water in the mortar that it will be impossible for the pipe to be filled with pulp or material 115 from the mortar. The passages extending from the gooseneck each way, to the adjacent mortars, form an inverted T-shaped passage, capable of being cleaned out by washing through the passage from compartment to compartment.

In this manner the danger of any pipe becoming choked up is avoided, and at the same time the water is discharged into the compartments in a small stream at opposite 125 sides of the dies which will cause such a stirring up or ebullition of the material around the die as will cause the pulp or waste material to be constantly carried away, and thereby permit of the deposition 130

around each die of the amalgam or more valuable particles of ore being crushed. The flow of water to the goose-necks can be regulated by a valve 24 between them and the 5 manifold 23.

In Fig. 9, the partitions 25 are formed integral with the feed-chute 26 and extend down to the bottom of the interior of the mortar where they are preferably seated in 10 channels 27 between the dies 8. In the construction shown in Fig. 10, the partitions 28 are formed separate from the feed-chute and are seated in channels 29 in the mortar with sufficient rigidity to hold them upright 15 between the respective stamp and dies.

As above described, it is evident that the feeding of the ore to the mortar can be much more uniform than where it is fed to the central stamp from the rear and distributed 20 from that point to the end stamps, and thereby the crushing capacity of the mill is correspondingly increased, and the danger of breakage caused by having the blows of the stamps expended at one side or edge, 25 which will also have a tendency to break the stem through uneven strain or pressure.

By feeding the ore centrally or around each stamp, a larger discharge area is secured, as the screens can be extended entirely 30 around the mortar; and by providing partitions between the different stamp and dies a more uniform result is secured, as the mortar is substantially divided into a series of single mortars each of which is fed, controlled and operated independently of all 35 of the others. Another advantage arising from feeding the ore around each stamp is that the process of feeding can be observed from any point around the mortar, and thereby any temporary choking up of any 40 one of the feed openings can be quickly remedied and thereby a more uniform feed is secured. It also permits of the ore and the ring forming a stem-guide which assists in 45 steadyng the stamp as it is reciprocated, and also reduces the height of the mortar to the lowest possible point and thereby correspondingly decreases its weight.

Having described my invention, I claim:—

1. The combination with a mortar and a plurality of stamps therein, of an ore receptacle surrounding the stamps and having downwardly extending ore feeding flanges, the planes of said flanges being inclined to the axis of the stamps, and provided with 55 apertures of greater diameters than those of the stamps to permit the passage of ore around the stamps.

2. In combination with a mortar a plurality of stamps and dies therein, a plurality of partitions in the mortar, each provided with a goose neck passage which terminates below the top of said dies, means to supply water to said passages, and ore feeding receptacles surrounding said stamps.

3. The combination with a mortar, stamps and dies, of partitions in the mortar forming separate compartments for each stamp, each of said partitions having a goose neck passage formed therein and terminating below the top of said dies in substantially a T-form to afford communication with each compartment, and means to supply water to said passages. 70

4. In combination with a mortar and a plurality of stamps therein, an ore receptacle surrounding the stamps and having its bottom formed with a plurality of openings to receive the stamps, said receptacle forming annular ore guides surrounding the 80 stamps, and said openings being eccentric to the respective stamps.

5. In combination with a mortar and a plurality of stamps therein, an ore receptacle surrounding the stamps and formed at its bottom with stamp-receiving openings eccentric to the respective stamps, the bottom of the receptacle being higher at the side where the space between the stamp and the receptacle is narrowest. 85 90

6. In combination with a mortar and a plurality of stamps therein, an ore receptacle surrounding the stamps and having its bottom extending at an inclination to the stamps and provided with openings to receive the stamps and to form ore guides surrounding the stamps, the space between the stamp and the receptacle being narrower on the higher side and being sloped inward toward the openings. 95 100

7. In combination with a mortar and a plurality of stamps therein, of an ore receptacle surrounding the stamps and provided with depressed flanges the planes of which are inclined to the axis of the stamps, said flanges having stamp receiving openings forming ore guides around said stamps. 105

8. In combination with a stamp mill mortar, stamps, and dies therein, of a plurality of partitions forming separate compartments for each stamp, and an individual ore feeding guide for and surrounding each stamp, said guides disposed at the top of said mortar. 110

9. The combination with a mortar, dies 115 and stamps working therein, of partitions in said mortar forming compartments each provided with an opening to afford communication with each compartment, and each partition having an upwardly and downwardly extending internal passage communicating with said opening, and means to supply water to said passage. 120

10. The combination, with a mortar provided with hollow partitions, of a goose-neck in each partition having openings in each side of the partition forming an inverted T-shaped passage communicating with the mortars at each side of the partition, said goose-neck extending upwardly and 125 130

then downwardly to the point of discharge, and stamps and dies between said partitions.

11. The combination with a mortar, dies and stamps working therein, of partitions in said mortar forming separate compartments for each stamp and die, each of said partitions having a horizontal opening on a plane lower than the face of said dies to afford communication with each compartment, each 10 partition also having an internal passage

communicating with said opening, and means to supply water to said passage.

In testimony whereof, I have hereunto set my hand at Los Angeles, California, this 8th day of February 1905.

EDWARD H. MOYLE.
